United States Patent Office

Des. 224,230

Patented July 11, 1972

224,230

DATA INPUT TERMINAL

James W. Kelso, Pacific Palisades, Calif., assignor to
MSI Data Corporation, Montclair, Calif.

Filed Dec. 7, 1970, Ser. No. 26,339

Term of patent 14 years

Int. Cl. D14—02

J.S. Cl. D26—5

FIG. 1

FIG. 2

FIG. 3

FIG. 1 is a front perspective view of a data input terminal showing my new design;

FIG. 2 is a right side elevational view thereof, the left side being substantially similar in appearance; and

FIG. 3 is a rear elevational view thereof.

I claim:

The ornamental design for a data input terminal, as shown and described.
